UNITED STATES PATENT OFFICE.

ALAN R. FERGUSSON, OF CHICAGO, ILLINOIS, ASSIGNOR TO DISCOUNT CHECK CORPORATION, OF NEW YORK, N. Y., A CORPORATION OF NEW YORK.

SAVING-CARD.

1,185,080.

Specification of Letters Patent.

Patented May 30, 1916.

Application filed February 4, 1915. Serial No. 6,197.

To all whom it may concern:

Be it known that I, ALAN R. FERGUSSON, a citizen of the United States, residing at Chicago, in the county of Cook and State of Illinois, have invented certain new and useful Improvements in Saving-Cards; and I do hereby declare the following to be a full, clear, and exact description of the invention, such as will enable others skilled in the art to which it appertains to make and use the same.

This invention relates to saving cards and has for an object to provide a card for use in banks and other saving institutions for conveniently taking care of and recording small amounts or installments paid in or deposited at stated intervals.

A further object of the invention is to provide a card adapted for use in such associations as Christmas saving clubs, travelers' saving clubs, or the like where the depositors deposit a stated amount weekly or at stated intervals until a given or aggregate amount has been reached or the time covered for which the said saving card was issued.

A further object of the invention is to provide a card embodying improved means for handling the business conveniently, expeditiously and accurately.

A further object of the invention is to provide a card which shows the exact amount which is to be deposited at each particular deposit period, the occurrence of the deposit period and the entire amount which has been deposited to and including the last deposit.

With these and other objects in view the invention comprises certain novel constructions, combinations and arrangement of parts as will be hereinafter more fully described and claimed.

In the drawings: Figure 1 is a view in perspective of the improved card showing the front member the amount to be deposited each week as one dollar and beginning at the first of September and continuing throughout the year, it being understood, however, that the length of the deposit period, the amount of the deposit and the continuity of such deposit is wholly immaterial to the present invention. Fig. 2 is a

view in elevation of the rear or second member of the card with the front member removed. Fig. 3 is a fragmentary view of the second or rear member showing a reversal of the amounts in Fig. 2, to give the amount still due after each deposit. Fig. 4 is a fragmentary view of the rear or back member as seen through the front member, exhibiting both the amount paid and the amount to be paid to complete the transaction.

Like characters designate corresponding parts throughout the several views.

In carrying into effect the present invention, a double card is employed embodying the members A and B joined along one edge as at C so that each registers accurately with the other when folded along such fold C.

The members A and B are provided with lines 10 and 11 to receive the name of the depositor, spaces 12 for the serial number of the card, similar spaces 13 properly designated to receive the amount of the periodical deposit, spaces 14 properly designated to receive the number of periodical deposits, spaces 15 properly designated to receive the date of the opening of the account. Below the spaces just above referred to a table is provided on both members containing the names of all of the months of the year with a column of ordinals of weeks contained in each of said months. Upon member A spaces 16 are provided opposite said ordinals and properly designated to receive the amounts of periodical deposits. Upon member B similar spaces 17 are provided for receiving total amounts governed by the amount of instalments received and noted in the spaces 16. As shown at Fig. 2 the amounts are intended to be the running total of the instalments paid as noted in the spaces 16. As shown at Fig. 3 the order is intended to be reversed so that the amounts made visible as hereinafter explained will show the running total due, or the amount still to be paid. As shown at Fig. 4 both the total paid and the total due are shown in the squares or spaces 17.

When a club is formed all the members of which are, for instance, pledged to pay a given amount for a given length of time, beginning at a given date, the cards will be printed and furnished to the banking insti-

tution with the numerals already applied thereto. Such ready printing would be as shown at Figs. 1 and 2 which have the entire amount filled in. The amounts on member B are the totals paid, with instalments at one dollar a week, and progress from one dollar at starting to fifty-two dollars at finish. If preferred, the same spaces 17 might contain a diminishing series of 10 amounts as indicated in Fig. 3, which would indicate the sums due or not paid, beginning with fifty-one dollars and decreasing to nothing. Or in some cases it may be preferred to have both series within the spaces 15 17, as indicated in Fig. 4, so that by punching out the front space 16 the entire rear space 17 is exposed and the amounts thereon may be read through the hole in the front member A. In Fig. 4 the total paid is disposed above the total due, but this arrangement is permissible so long as the two sums are sufficiently small to be seen through the one hole or window.

It often happens, however, that all of the 25 members of a club do not begin payments at a given time or do not pay like amounts or continue the payments for the same period. Under these conditions the cards are furnished to the bank in blank and could 30 be filled in with a pen, typewriter or rubber stamp. If the latter, a stamp carrying the proper figure is inked in the usual manner and used to print into the spaces 16 the amount of deposit of that particular depositor. The cumulative totals paid or to be paid, or both, as shown at Figs. 3 and 4 are then printed in in like manner by the use of a stamp if preferable but more probably it will be found convenient to fill in such data 35 upon a typewriter as these totals will vary according to the amount of deposit.

Whatever the system and however the card is filled it is used by employing a hand punch or other mechanism for cutting out 45 of the card A each of the instalment payments when it is deposited as indicated more particularly at Fig. 4, producing thereby a window through which the amount in the spaces 17 of the card B are visible. If the 50 cards are used as shown at Figs. 1 and 2 it is obvious that cutting out each of the instalments of one dollar will disclose beneath that an amount equal to the cumulative deposit of the several one dollar instalments; *i. e.* the total paid. As shown at Fig. 4 four of such windows are cut out and card B shows four dollars paid and forty-eight dollars to be paid. If the amount to be paid is not filled in on card B it is obvious 55 that the amount shown through the windows will be simply the total paid. If the amounts to be paid only are filled in on card B then such amounts will be shown through the windows in the order shown at Fig. 3.

The depositor carries the card with him 65 and each time he presents a deposit he presents the card and the receiving teller cuts out from card A the amount of his deposit thereby making a record upon the card itself of the exact instalment paid. Through the 70 hole in this card is then visible the total paid up to that time and the total amount to be paid, or both, depending upon the use of the numerals in the spaces 17 on card B.

It is wholly immaterial to the present invention whether the cards are furnished to the bank printed in full or whether they are furnished in blank and a pen, typewriter, or stamp used for completing the card at the bank before it is issued to the depositor. 75 80

I claim:

1. A saving card comprising two members hinged together and folded into contact, the upper member being provided with a series of spaces for the amounts of instalment payments; and the lower member being provided with spaces registering with those mentioned and adapted to contain a progressive series of amounts whereof each is the total of all said payments on the upper 85 member from that in its corresponding space to one end of its series inclusive, the totals being visible when the instalment spaces are punched.

2. A saving card comprising two members hinged together and folded into contact, the upper member being provided with a series of spaces for the amounts of instalment payments, and with adjacent designations of the dates they fall due; and the lower member being provided with spaces registering with those mentioned and adapted to contain a progressive series of running total amounts, each being the sum of all payments made from the date of the first to and including the date of that payment in the overlying space on the upper member, and the totals being visible when the instalment spaces are punched. 100 105

3. A saving card comprising two members 110 of like dimension, one overlying the other, the upper member being provided with a series of spaces containing the amounts of instalment payments; and the lower member being provided with a series of spaces 115 registering with those mentioned and each containing two amounts whereof one is the total of the instalment payments from the beginning up to that point, and the other is the total of the instalments as yet unpaid 120 from that point to the finish of the series on the upper member, both totals being visible when the space in the upper member is punched.

4. In a saving card, two members hinged 125 together, the first being provided with spaces properly designated to receive repetitions of like amounts at like intervals; and the sec-

ond member being provided with spaces reg-
istering with the spaces of the first member
and visible therethrough when the amounts
are cut from the first member, the spaces of
5. the second member being provided with nu-
merals cumulative of the numerals appear-
ing upon the first member.

In testimony whereof I affix my signature
in presence of two witnesses.

ALAN R. FERGUSSON.
